[57] ABSTRACT

A mechanism for substantially instantaneously reversing the direction of rotation of a shaft. A pair of drive members are freely rotated about the shaft and an interconnection assembly is mounted for rotation with the shaft between the drive members. The interconnection assembly includes a pin having opposed, tapered ends which engage mating recesses in the drive members. The pin is sufficiently long that, as it moves from one drive member to the other, one end enters a recess in one adjacent drive member before the other exits from a recess in the other drive member. The pin is reciprocated by a hydraulic cylinder and piston through a linkage which is reciprocated by the piston and rotates with the shaft.

SHAFT ROTATION REVERSING DEVICE**BACKGROUND OF THE INVENTION**

It is often desired in various machines to reverse the direction of rotation of some portion of the machine in an essentially instantaneous manner, i.e., essentially without any lost motion. For instance, in various winding machines an arbor is rotated as a winding head is moved longitudinally of the arbor for winding material about the arbor. It often is desirable to instantaneously reverse the winding head at each end of its stroke. In order to do this it is necessary to reverse the direction of rotation of the drive for the winding head.

SUMMARY OF THE INVENTION

Accordingly it is an object of the present invention to provide an improved motion reversing mechanism.

It is another object of this invention to provide such a mechanism which will substantially simultaneously reverse the direction of rotation of a shaft.

Yet another object of this invention is to provide such a mechanism which is simple and rugged in construction and yet reliable in operation.

In carrying out the invention, in one form thereof there is provided a motion reversing mechanism, including a rotatable output shaft. A first drive member is freely rotatable in a first direction about the output shaft and a second drive member is freely rotatable in a second direction about the output shaft. Interconnection means is mounted for rotation with the output shaft, between the drive members, and selectively interconnects the output shaft with one of the drive members for rotating the output shaft in a predetermined direction. The interconnection means is adapted to engage one of the drive members as it disengages from the other drive member so that the direction of rotation of the output shaft reverses substantially instantaneously.

BRIEF DESCRIPTION OF THE DRAWING

The subject matter which I regard as my invention is particularly pointed out and distinctly claimed in the concluding portion of the specification. The invention itself, however, together with further objects and advantages thereof, may be better understood by reference to the following description taken in conjunction with the accompanying drawing in which:

FIG. 1 is a plan view of a shaft reversal mechanism incorporating one embodiment of the present invention, the view being partly broken away and partially in section for purposes of illustration; and

FIG. 2 is an elevational view generally as seen along line 2-2 of FIG. 1.

DESCRIPTION OF THE PREFERRED EMBODIMENT

Referring now to the drawing there is illustrated various features of an exemplification motion reversing mechanism 10 which incorporates one embodiment of the present invention. Various components of the mechanism 10 are enclosed in and supported by a housing 11. The housing may include side walls 12-15, a bottom wall 16, and a top wall 17. Additionally flanges, 18 and 19 may be attached to side walls such as 12, 14 for mounting the mechanism in a machine. An input shaft 20 is rotatably supported in a suitable opening in side wall 13 by means of a low friction bearing assembly 21. Bearing 21 is supported about the

shaft 20 so that the shaft may rotate within the bearing while it is restrained from longitudinal movement by means of a conical retainer 22, which is threadably mounted on the shaft 20 and engages the bearing assembly 21. The input shaft 20 is rotated from a suitable power source (not shown) by means of a sprocket assembly 23 which is mounted to rotate with the shaft 20. A drive chain for instance may be connected between the sprocket assembly 23 and to the power source so that, as the power source rotates, the input shaft 20 also rotates.

A bevel gear 24 is mounted to rotate with the inner end of the drive shaft 20. A mating bevel gear 25 is securely mounted on an intermediate shaft 26 by any suitable means such as pin 27 to rotate with the intermediate shaft. The ends of intermediate shaft 26 are rotatably supported in the side walls 12, 14 by means of a pair of bearing assemblies 28 and 29. A gear assembly 30 is mounted on the shaft 26 to rotate therewith by some means such as pin 31 for instance. Also, a sprocket assembly 32 is mounted on the shaft 26 to rotate therewith. With this arrangement, as bevel gear 24 drives bevel gear 25, the gear assembly 30 and sprocket assembly 32 will rotate in the same direction with the shaft 26.

An output shaft 35 is mounted between the walls 12, 14 in spaced relationship to shaft 26 by means of bearing assemblies 36, 37. A first drive means, in the form of a gear assembly 38, is mounted on the shaft 35. The gear assembly 38, by way of exemplification, includes a hub 39 which is freely rotatably mounted about the shaft 35 by means of a bearing such as 40 at each end of the hub. Additionally, the hub is held in axial position on the shaft by means of a conical retainer 41 which is threaded to the shaft and bears against the hub 39. The gear assembly 38 also includes a gear 42 having teeth which mesh with the teeth of gear 30 so that, as the gear 30 rotates with the shaft 26, gear assembly 38 is rotated.

A second drive means, in the form of a sprocket assembly 43, is freely rotatably mounted about shaft 35 by means of a suitable bearing, not shown, and is held against axial movement by means of a conical retainer 44 which is threaded on the shaft 35 and bears against the sprocket assembly. The sprocket assembly 43 is spaced from gear assembly 38 and includes a sprocket wheel 45 which is in alignment with the sprocket wheel of assembly 32. The two sprocket wheels are connected by means of a suitable chain 46. Thus, when sprocket assembly 32 rotates with the shaft 26, sprocket assembly 43 is rotated by chain 46. It will be understood that connection of sprocket assembly 43 with sprocket assembly 32 by means of chain 46 causes sprocket assembly 43 to rotate in the same direction as intermediate shaft 26 while the meshing of the gears of gear assembly 30 and 38 will cause gear assembly 38 to rotate in a direction opposite to intermediate shaft 26.

An interconnection means or assembly 50 is positioned between the gear assembly 38 and the sprocket assembly 43 and is rotatable with the shaft 35. In the exemplification mechanism the interconnection assembly includes a pair of side plates or members 51 and 52 which are connected to the shaft 35 by means of pin 53 that rotate with the shaft. The side plates 51, 52 are firmly attached by screws or bolts 54. The shaft 35 and plates 51, 52 define a slot or opening 61 which extends transversely of the longitudinal axis of shaft 35. The

shaft 35 also is provided with an axially extending internal slot or opening 62 which extends inwardly from the left end of the shaft (as seen in the FIGS.) into alignment with the slot 61. Additionally, side plate 51 is provided with a slot or opening 55 which extends generally longitudinally of the shaft 35 in alignment with the hub 39 of the gear assembly 38 and the hub 47 of sprocket assembly 43. The hub 39 is provided with a number of tapered or conical recesses 56 which are in radial alignment with the slot in side plate 51. Similarly hub 47 is provided with a plurality or conical openings 57 which also are in radial alignment with slot 55. The number of recesses 56 and 57 may be varied depending on the number of times per revolution of the shaft 35 it is desired to have the opportunity to reverse the direction and rotation of the shaft.

A pin or pin assembly 58 is received in the slot 55 of side plate 51 and includes tapered or conical pin portions 59 and 60 which are complimentary in shape to the recesses 56 and 57 so as to fit snugly within the recesses. When the pin portion 60 engages one of the recesses 57 in hub 47 the interconnection assembly 50, and thus the shaft 35 is operatively connected to the sprocket assembly 43 and shaft 35 rotates in one direction with a sprocket assembly 43. When pin portion 59 is received in one of the recesses 56 in hub 39, the interconnection assembly 50 and thus the shaft 35 is operatively connected to the gear assembly 38 and the shaft 35 rotates in the other direction with the gear assembly. The pin or pin assembly 58 is made longer than the width of side plate 51. Preferably pin 58 is of sufficient length that when one of the pin portions 59, 60 is fully received in a corresponding recess 56, 57, the other pin portion will just be within the side plate 51 and will not interfere with the other of the assemblies 38, 43.

It will be understood that, with the mechanism as thus far described, the direction of rotation of shaft 35 may be reversed any time a recess 56 and a recess 57 both come into alignment with the slot 55. The reversal of the direction of rotation of the shaft 35 is accomplished by moving pin 58 longitudinally of the shaft 35 so as to change from an engagement of pin portion 59 in a recess 56 to engagement of pin portion 60 in a recess 57, or vice versa. It will be seen from FIG. 1 that, as the pin 58 moves axially of the shaft one of the pin portions 59, 60 will enter the associated recess 56, 57 before the other pin portion clears its associated recess. Thus at one moment the shaft 35 is connected to one of the assemblies 38, 43 and at the next moment it is connected to the other of assembly 38, 43. This causes the reversal of direction of rotation of the shaft 35 to be substantially instantaneous.

An actuation means or assembly is provided for moving pin 58, and axially of the shaft 35; which moves pin portions 59, 60 jointly. This actuation assembly includes a first arm 63 which is pivotally mounted to side plate 52 within slot 61 by means of a pin 64. The distal end 65 of the arm 63 is received within a slot or opening 66 in the pin 58. As the arm 63 is pivoted about pin 64 the distal end 65 will move the pin 58 generally axially of the shaft 35. A second arm 70 is pivotally attached to the arm 63 by means of a pin 71 and extends axially within the slot 62. For ease of assembly the second arm 70 maybe in the form of a flat or generally rectangular member connected to a generally cylindrical arm 72 by means of a pin 73. The third or cylindri-

cal arm 72 extends axially of the slot 54 and out of the shaft 35 and thru the bearing 37. An additional bearing assembly 74 is mounted to the distal end of the arm 72. The bearing assembly 74 and its mounting to the arm 72 is such that the bearing assembly will move the arm 72 axially of the shaft 35 while, at the same time, allowing the arm 72 to rotate within the bearing assembly 74.

An actuator in the form of a reversible, fluid actuated cylinder 75 in the exemplification, is mounted to the side wall 15. The piston 76 of the hydraulic cylinder is pivotally connected to an intermediate arm 78 by a pin 77. The arm 78 is pivotally attached to a support bracket 79 by means of a pin 80 which is carried by the intermediate arm 78 and a elongated slot 81 in the bracket 79. The other end of the arm 78 is bifurcated to form a pair of fingers 82 and 83 which straddle the bearing assembly 74. Each of the fingers 82, 83 is operatively connected to the bearing assembly 74 by means of bolts 84, 85 which extend thru the fingers 82, 83 and are received in the bearing assembly 74.

With this mechanism, as the cylinder 75 is actuated from a suitable reservoir of fluid, the piston 76 is selectively extended or retracted. This causes the arm 78 to pivot about the pin 80 so as to move the bearing assembly 74 selectively toward or away from the side wall 14. This movement of the bearing 74 causes cylindrical arm 72 and rectangular arm 70 to move within the slot 62 in shaft 35. Arm 70 pivots arm 63 about pin 64 so that the distal end 65 of the arm 63 moves the pin longitudinally of the shaft 35 so as to change the operative connection of the interconnection assembly 50 from one to the other of the drive assemblies 38, 43. This effectively instantaneously reverses the direction of rotation of the shaft 35.

Preferably the actuation of cylinder 75 will be controlled so as to occur when the recess 56, 57 into which the pin portion 59, 60 is to be engaged is in alignment with the slot 55. Close control of this timing will reduce the wear on the mechanism. However, it will be understood that with proper construction and selection of materials to prevent excessive wear, cylinder 75 may be actuated at any time. Initially essentially no movement will occur as the distal end of pin portion 59 or 60 will ride against the adjacent surface of hub 39, 47. When the next recess 56, 57 comes into alignment with the pin portion 59, 60, depending on the direction in which cylinder 75 is tending to move the pin 58, the pin will snap from one of its extreme positions to its other extreme position. This essentially instantaneously reverses the direction and rotation of the shaft 35.

The present invention has been described by reference to a preferred embodiment thereof, it is to be understood, however, that modifications may be made therein by those skilled in the art without actually departing from the true spirit and scope of the invention.

What I claim is new and desire to secure by Letters Patent in the United States is:

1. A motion reversing mechanism, including:
  - a. rotatable output means;
  - b. first drive means rotatable in a first direction;
  - c. second drive means rotatable in a second direction; and
  - d. interconnection means rotatable with said output means and movable between a first position, operatively interconnecting said output means to said first drive means, and a second position, opera-

- tively interconnecting said output means to said second drive means;
- e. said interconnection means being adapted to move into operative connection with one of said drive means as it moves out of operative connection with the other of said drive means for effecting substantially instantaneous reversal of the direction of rotation of said output means.
2. A motion reversing mechanism as set forth in claim 1 wherein each of said first and second drive means defines at least one recess therein; said interconnection means includes first and second pin portions for selective insertion into said at least one recess in each of said first and second drive means respectively; one of said pin portions entering a corresponding recess before the other of said pin portions exits a corresponding recess as said interconnection means moves between its first and second positions.
3. A motion reversing mechanism as set forth in claim 2 wherein said recesses and said pin portions are provided with mating tapers.
4. A motion reversing mechanism, including:
- a rotatable output shaft;
  - a first drive member freely rotatable about output shaft in a first direction;
  - a second drive member freely rotatable about said output shaft in a second direction; and
  - interconnection means mounted for rotation with said output shaft between said first and second drive members; said interconnection means selectively interconnecting said output shaft with a predetermined one of said drive members for rotating said output shaft with the predetermined one of said drive members;
  - said interconnection means being adapted to engage one of said drive members as it disengages from the other of said drive members for substantially instantaneously reversing the direction of rotation of said output shaft.
5. A motion reversing mechanism as set forth in claim 4, further including:
- rotary input means;
  - first transfer means operatively connecting said

- first drive member to said input means for rotation in a first direction; and
- c. second transfer means operatively connecting said second drive member to said input means for rotation in a second direction.
6. A motion reversing mechanism as set forth in claim 4, wherein:
- each of said drive members includes at least one recess disposed toward said interconnection means;
  - said interconnection means includes opposed pin portions concurrently reciprocable longitudinally of said output shaft for selective engagement in said at least one recess in each of said drive members;
  - said pin portions being spaced apart sufficiently that one of said pin portions enters a corresponding recess in one of said drive members before the other of said pin portions exits from a corresponding recess in the other of said drive members.
7. A motion reversing mechanism as set forth in claim 6, wherein; said recesses and said pin portions are provided with mating tapers.
8. A motion reversing mechanism as set forth in claim 6, wherein:
- said interconnection means includes a support mounted for rotation with said output shaft;
  - said pin portions are mounted for joint reciprocating movement within said support; and
  - actuation means is provided for said pin portions, said actuation means being selectively energizable for reciprocating said pin portions,
9. A motion reversing mechanism as set forth in claim 7, wherein; a first arm is mounted for pivotal movement within said support to reciprocate said pin portions; a second arm is connected to said first arm and extends axially of said output shaft for pivoting said first arm; and power means is connected to said second arm for moving said second arm longitudinally of said output shaft while allowing rotation of said second arm with said output shaft.
